(57) **CLAIM**

The ornamental design for a door handle, as shown and described.

DESCRIPTION

FIG. 1 is front view of a door handle according to the present invention.

FIG. 2 is a top view of the door handle depicted in FIG. 1, the bottom view being a mirror image thereof.

FIG. 3 is a right side view of the door handle depicted in FIG. 1.

FIG. 4 is a left side view of the door handle depicted in FIG. 1; and,

FIG. 5 is a perspective front, bottom and right side view of the door handle depicted in FIG. 1.

The broken line showing of the escutcheon plate is for illustrative purposes only and forms no part of the claimed design.
